U.S. Appl. No. 16/385,145, filed Apr. 16, 2019.

Primary Examiner — Lauren R Calve

(74) Attorney, Agent, or Firm — Baker Botts L.L.P.

(57) **CLAIM**

The ornamental design for a tamper-evident feature for a container, as shown and described.

DESCRIPTION

FIG. 1 is a perspective view of a tamper-evident feature for a container of our design;

FIG. 2 is a perspective view of the tamper-evident feature for a container of FIG. 1, shown in an open position;

FIG. 3 is a back view of the tamper-evident feature for a container of FIG. 1;

FIG. 4 is a front view of the tamper-evident feature for a container of FIG. 1;

FIG. 5 is a side view of the tamper-evident feature for a container of FIG. 1;

FIG. 6 is a side view of the tamper-evident feature for a container of FIG. 1;

FIG. 7 is a top view of the tamper-evident feature for a container of FIG. 1; and,

FIG. 8 is a bottom view of the tamper-evident feature for a container of FIG. 1.

The broken lines shown in the Figures are included for the purpose of illustrating the environment and boundaries and form no part of the claimed design.

1 Claim, 8 Drawing Sheets
